COMBINATION WHIPPED CREAM AERATOR AND DISPENSER OR THE LIKE

John A. Werry, Cedar Grove, N. J., assignor to Kidde
Textile Machinery Corporation, a corporation of Delaware

Application November 14, 1955, Serial No. 38,882

Term of patent 14 years

(Cl. D2—3)

Fig. 1

Fig. 1 is an elevational view illustrating one side of a combination whipped cream aerator and dispenser or the like, embodying my new design, the other side being substantially the same; and

Fig. 2 is a top plan view.

The dominant features of the design reside in the portions shown in full lines.

I claim:

The ornamental design for a combination whipped cream aerator and dispenser or the like, substantially as shown and described.
